UNITED STATES PATENT OFFICE.

RICHARD T. NEWTON, OF NEW YORK, N. Y.

REBOUND CHECK.

Application filed November 13, 1922. Serial No. 600,649.

To all whom it may concern:

Be it known that I, RICHARD T. NEWTON, a citizen of the United States of America, residing at New York city, borough of Manhattan, in the county of New York and State of New York, have invented certain new and useful Improvements in Rebound Checks, of which the following is a specification.

My invention relates to rebound checks, and particularly to a device of this type for use on an automobile, or other vehicle having a body spring supported from the running gear. The object of my invention is to provide a device which is simple to manufacture, efficient in operation, and affords certain advantages in operation hereinafter pointed out, or apparent from the accompanying drawings, in which—

Fig. 1 is a side elevation of portion of a vehicle to which my invention in one form is applied;

Fig. 2 is a broken side elevation of the rebound check device shown in Fig. 1, but drawn to a larger scale;

Fig. 3 is a perspective of the friction shoe;

Fig. 4 is a front elevation of the friction drum;

Fig. 5 is a vertical section through the device in assembled position and under stress;

Fig. 6 is an inverted plan, viewed from the direction indicated at 6—6, Fig. 5;

Fig. 7 is a section similar to Fig. 5, but showing the parts in release position;

Fig. 8 is a face view of the frame;

Fig. 9 is a side elevation thereof;

Fig. 10 is a broken section through a modified construction; and

Fig. 11 is a section on the line 11—11, Fig. 10.

The present rebound check device may be adapted to various types of vehicles, and to various constructions in vehicles of the same type. I have shown it in the accompanying drawings adapted particularly for use on automobiles. Its mounting on the latter may be variously modified, but I have illustrated, for example, a carrying bracket 15 adapted to be secured to a chassis side bar 16 in any suitable way, as by means of a bolt 17 passing therethrough, and a supporting lug or hook 18 overlying the upper flange of the side bar to assist in rigidly securing the bracket thereto. The frame 19 of the device may be in the form

of a disc appropriately tapped to receive screw bolts 20, by which it is secured to the bracket 15. On the frame is a fixed stud 21, surrounded by an anti-friction bearing bush 22.

Mounted eccentrically on the stud by the bearing 23, is what may for convenience be termed a friction drum 24, the oscillation of which on the stud is limited by a stop pin 25 on the frame 19, which engages in a slot 26 in the side web 27 of the drum. The web 27 carries a spring anchor pin 28 to which is secured one end of the spiral return spring 29. To the opposite and free end of the return spring is secured one end of the friction band 30, which passes through the interrupted area 31 of the drum and around the periphery of the latter, being carried down therefrom to any suitable attaching means by which the other end of the friction band is secured to the running gear. In the present example I have shown this end of the band attached to a clamp 32 mounted beneath and secured to the wheel axle 33 by a clamping bolt 34.

Also mounted on the stud 21 is a friction shoe 35, here shown integral with the side flange 36, which terminates in a pair of bearing lugs 37 straddling the bearing 23 of the friction drum on the stud 21. The side flange 36 of the shoe is laterally offset from the bearing lugs 37 to clear the side margin of the drum, and the parts are so proportioned that in assembled position the shoe partially surrounds the drum and is circumferentially spaced from the latter a sufficient distance to accommodate between them the friction band 30. At the free end of the shoe are provided abutment lugs 38 pierced to receive the pin 39 by which the anchor bolt 40 is secured thereto. The latter passes through the eye 41 in the offset stop lug 42 of the frame 19, and has screwed thereon a thrust nut 43, between which and the stop lug 42 is interposed a pressure spring 44. The nut 43 may be provided with a graduated scale 45 (see Fig. 6) with which cooperates the pointer 46 secured to the stop lug 41 on the frame 19. The position of the nut with respect to the pointer may be thus used to indicate the degree of stress placed upon the spring 44, the effort of which may thus be regulated to vary the frictional grip on the band 30 in accordance with the weight of the chassis and its associated car body elements.

The operation of the rebound check is as follows. The normal position of the parts is indicated in Fig. 7. In this position the return spring 29 is under slight stress and has wound upon its f the attached end of the friction band 30, thus taking up any slack therein. It also exerts an effort, through the band, upon the drum 24 in the direction indicated by the arrow X, Fig. 7.

10 The drum is consequently biased away from the shoe 35, but is halted by the stop pin 25 which engages at one end of the slot 26 in the web of the drum. The shoe 35 is stressed in the same direction by its spring 44, but is prevented from following the drum by the impingement of its stop lugs 38 against the stop lug 42 of the frame. The friction band 30 is thus free to play in the circumferential space afforded between 20 the exterior of the drum and the adjacent inner face of the shoe. On the upward throw of the chassis 16 with respect to the running gear or axle 33, however, the band 30 is pulled downward at its running gear end, while its opposite end is held in contact with the drum by the stress of the spring 29. The drag thus exerted upon the drum overcomes the pull of the spring 29 and tends to swing the drum bodily in the 25 direction of the arrow Y (Fig. 5) on the bearing stud 21. This rocks the drum towards the shoe and engages the friction strap between the opposed surfaces of the shoe and drum with a friction grip dependent upon the stress of the pressure spring 44. The upward throw of the chassis is thus checked.

It is obvious that the length of the slot 26 in which the stop 25 plays may be varied. 40 I have indicated it as rather short in order to prevent the throw of the drum against the shoe to an extent which might cause the latter to swing outward a sufficient distance to rupture the housing 47 which is mounted 45 upon the frame 19. This casing encloses the parts except for apertures 48 to permit the play of the band, and 49 to accommodate the stop lug 42, pressure spring 44; and the associated parts of the shoe. The housing 50 may be shaped if desired to wholly enclose the latter save for the opening 48 through which the friction band 30 passes.

It will be obvious from the foregoing that the shoe and drum form in effect two cam 55 members swinging on the axis 21 and engaging between them the friction band 30. The shoe 35 forms a yielding abutment, the resistance of which is determined by the spring 44, while the drum 24 is forced out 60 against this yielding abutment by the drag of the friction band and the eccentric mounting of the drum. A quick grip upon the friction band is secured by the construction, while at the same time the checking effect

is not objectionably sudden, since the shoe 65 is yieldably restrained and imposes its gripping effort progressively on the strap.

The device is simple to manufacture, assemble and install; it is not readily put out of order, and is efficient in operation.

In Figs. 10 and 11 I have shown a modified construction, in which the shoe 50 is rigid with the base and only the drum swings. In order to force the drum away from the shoe after the checking action is completed, I provide a spring 51 housed in a boss 52 rigid with the frame and acting on the drum through a plunger 53 and strut 54. In order to take up wear, the strut may have 70 associated with it a pawl 55 rigid with the strut axis 56 and pressed by the leaf spring 57 against the inner face of the strap. As the strap wears and becomes thinner, the change in position of the pawl 55 causes the link 54 to change its angular position with 75 respect to the plunger 53. Obviously, in this construction the pull on the strap 30 throws the drum out against the rigid abutment shoe 50. To insure the immediate 80 freeing of the drum and the consequent winding-up of the strap 30 at the end of the checking action, the drum is forced by the spring 51 away from the fixed abutment shoe 50, thus permitting the strap to freely 85 slip around the drum and wind up on the spiral return spring 29.

This modification involves the same idea of an eccentrically mounted drum moving against an abutment under the pull of the friction band, to obtain a gripping action 90 on the latter. I prefer, however, the construction first shown with the yielding abutment, since a gentler action is thus secured, and there is less danger of injury to the 95 parts.

It will of course be understood that the 100 position of the parts may be reversed—that is to say, that the frame of the rebound check may be mounted on the running gear, and the attaching end of the friction band 105 may be secured to the chassis—and the claims are to be understood to cover this 110 equivalent.

It may be pointed out further that the pin and slot connection 25—26 in the construction shown in Figs. 1—9, and the strut 54 in Figs. 10—11, serve to limit the throw of the drum against the associated abutment member, viz., the shoe 35 in the one case, and the casing 50 in the other case. Too strong a grip on the band between these friction surfaces is thus prevented.

Various detail changes may be used in the construction which will be obvious to those skilled in the art. For example, the stud 28 which carries the return spring may be mounted on the frame instead of on the drum, without altering its function; of

course the web of the drum would necessarily be cut out to clear the pin if this construction were used. The embodiments of my invention illustrated and described, constitute but examples, which may be variously modified while operating upon the same principle, and without departing from the underlying conception which I claim as my invention.

10 I claim—

1. A rebound check device comprising a frame adapted to be mounted on the body portion of a vehicle, a friction drum eccentrically mounted on said frame, a friction band surrounding said drum and adapted to be drawn into gripping engagement with and to swing the same, an abutment member cooperating with said friction member and toward which the latter is swung by said band when in gripping engagement therewith, and means for securing the end of said band to the running gear of the vehicle.

2. A rebound check device comprising a frame adapted to be mounted on the body portion of the vehicle, a friction member eccentrically mounted on said frame, a friction band adapted to be drawn into gripping engagement with said friction member and to swing the same, a yielding abutment member cooperating with said friction member and toward which the latter is swung by said band when in gripping engagement therewith, and means for securing the end of said band to the running gear of the vehicle.

3. A rebound check device comprising a frame adapted to be mounted on the body portion of a vehicle, a friction drum eccentrically mounted on said frame, a friction band surrounding said drum and adapted to be drawn into gripping engagement with and to swing the same, an abutment member cooperating with said friction member and toward which the latter is swung by said band when in gripping engagement therewith, and means for securing the end of said band to the running gear of the vehicle, together with a return spring coiled within the drum for taking up slack in the band on the approach of the running gear and body portions of the vehicle toward each other.

4. A rebound check device comprising a frame adapted to be mounted on the body portion of a vehicle, a friction member eccentrically mounted on said frame, a friction band adapted to be drawn into gripping engagement with said friction member and to swing the same, an abutment member cooperating with said friction member and toward which the latter is swung by said band when in gripping engagement therewith, and means for securing the end of said band to the running gear of the vehicle, together with a return spring for taking up slack in the band on the approach of the

running gear and body portions of the vehicle toward each other, said return spring exerting a biasing effort on said friction member through said band to move the friction member away from said abutment 70 member.

5. A rebound check device comprising a frame adapted to be mounted on the body portion of a vehicle, a friction member eccentrically mounted on said frame, a friction band adapted to be drawn into gripping engagement with said friction member and to swing the same, an adjustably yielding abutment member cooperating with said friction member and toward which the latter is swung by said band when in gripping engagement therewith, and means for securing the end of said band to the running gear of the vehicle.

6. A rebound check device comprising a frame adapted to be mounted on the body portion of a vehicle, a friction member eccentrically mounted on said frame, a friction band adapted to be drawn into gripping engagement with said friction member and to swing the same, an abutment member cooperating with said friction member and toward which the latter is swung by said band when in gripping engagement therewith, a spring urging said abutment member toward the friction member, stop means limiting the approach of the abutment member toward the friction member under the effort of said spring, and means for securing one end of said band to the 100 running gear of the vehicle.

7. A rebound check device comprising a frame adapted to be mounted on the body portion of a vehicle, a friction member eccentrically mounted on said frame, a friction band adapted to be drawn into gripping engagement with said friction member and to swing the same, an abutment member cooperating with said friction member and toward which the latter is swung by said band when in gripping engagement therewith, a spring urging said abutment member toward the friction member, stop means limiting the approach of the abutment member toward the friction member under the effort of said spring, means for varying the initial stress of said spring, and means for securing one end of said band to the running gear of the vehicle.

8. A rebound check device comprising a frame adapted to be mounted on the body portion of a vehicle, a friction member eccentrically mounted on said frame, a friction band adapted to be drawn into gripping engagement with said friction member and to swing the same, an abutment member cooperating with said friction member and toward which the latter is swung by said band when in gripping engagement therewith, a spring urging said 130

abutment member toward the friction member, stop means limiting the approach of said spring, means for varying the initial stress of said spring, means for indicating said stress, and means for securing one end of said band to the running gear of the vehicle.

9. A rebound check device comprising a pair of members having substantially concentric friction surfaces of substantially the same curvature, one of said members being eccentrically mounted in combination with a friction band arranged between said surfaces and serving by its drag upon said eccentrically mounted member to swing the same toward the cooperating member to grip the band between them together with

resilient means opposing the displacement of said cooperating member.

10. A rebound check device comprising a pair of members having substantially concentric friction surfaces of substantially the same curvature, one of said members being eccentrically mounted, and the other being yieldably held with respect thereto, in combination with a friction band arranged between said surfaces and serving by its drag upon said eccentrically mounted member to swing the same toward the cooperating member to grip the band between them.

In testimony whereof I have signed my name to this specification.

RICHARD T. NEWTON
